GRINDING TOOL

Toshio Mikiya, Tokyo, Japan, assignor to Nitto Kohki
Company, Limited, Tokyo, Japan

Filed Aug. 6, 1968, Ser. No. 13,048

Claims priority, application Japan Mar. 9, 1968

Term of patent 14 years

Int. Cl. D8—02

U.S. Cl. D8—62

FIG. 1.

FIG. 2.

FIG. 3.

FIG. 4.

FIG. 5.

FIG. 6.

FIG. 7.

FIGURE 1 is a side elevational view of a grinding tool embodying my design;

FIGURE 2 is a side elevation opposite to FIGURE 1;

FIGURES 3 and 4 are opposite plan views of the tool;

FIGURE 5 is a front elevational view of the tool;

FIGURE 6 is a rear elevational view of the tool; FIGURE 7 is a side elevational view thereof, wherein the handle portion is shown in an alternate adjustable position relative to the belt portion.

I claim:

The ornamental design for a grinding tool, as shown and described.
